ABSTRACT

Thread cutting device for double stitch sewing machines having a looper turning in a horizontal plane, a bobbin housing secured against turning movements by means of a retaining finger resting against an abutment in the stitch plate, an outlet opening for the looper thread determining the course of the looper thread between stitch plate and bobbin housing and a thread catcher having a point cooperating with a cutter and movable in a horizontal plane where the outlet for the looper thread is disposed below the plane of the surface of the bobbin housing at its wall facing the needle, preferably in the area of the retaining finger, and the point of the thread catcher is movable below the plane of the surface of the bobbin housing between the path of movement of the needle and the retaining finger of the bobbin housing.

ARRANGEMENT FOR CUTTING THREADS ON DOUBLE STITCH SEWING MACHINES

BACKGROUND OF THE INVENTION

The invention relates to thread cutting devices for sewing machines. More in particular, the invention concerns a thread cutting arrangement for double stitch sewing machines having a looper or catcher that rotates in a horizontal plane, a bobbin housing mounted in the looper against rotary movements secured by means of a retaining finger that rests against an abutment on the stitch plate, with an outlet for the looper thread that determines the course of the looper thread between the stitch plate and the bobbin housing, and a thread catcher movable in a horizontal plane that cooperates with a cutter, with a catcher point and a recess formed thereon for receiving the needle and the looper thread.

In a known thread cutting device a thread catcher that is movable above the bobbin housing surface is provided which is pivotally movable about an axis that is disposed generally parallel to the looper shaft. The point of the thread catcher is offset rectangularly and provided with a V-shaped incision where the two legs of the thread catcher defined by the incision are moved in an essentially vertical plane between the bobbin housing and the retaining finger that extends laterally and upwardly from its housing surface and seize the needle thread, as well as the looper thread during the first part of the thread catcher movement. The two threads seized are disposed during the further course of the thread catcher movement in front of an aperture that extends from the intersection of the two legs of the V-shaped incision and are guided and severed by a cutter entering this aperture. The arrangement of the two legs is such that the upper leg of the thread catcher moves above the plane of the bobbin housing surface and the lower leg below the plane of the bobbin housing surface. In this manner, it is insured that during the thread catching movement of the thread catcher, the thread that leaves the aperture at the top side of the bobbin housing and leads from there to the stitch hole, as well as also the part of the needle thread loop that rests during the guiding of the needle thread around the bobbin housing on its upper side is seized. The part of the needle thread loop that is moved during the guiding of the needle thread about the bobbin housing over its upper side is with loopers of this type of construction always the thread supply leading to the needle thread loop so that this thread catcher seizes and cuts the looper thread and the part of the needle thread loop that leads to the thread supply. The part of the needle thread loop leading to the sewing material extends during the thread catching movement of the thread catcher along the lower part of the bobbin housing and thence below the bobbin housing stop finger between the surface of the bobbin housing and the inside of the looper body to the stitch hole and cannot be seized by the thread catcher that moves along a path of movement extending between the retaining finger and the housing surface of the bobbin housing. With the older arrangement the threads are severed almost centrally at their seizing location by the cutter that dips into the aperture of the thread catcher so that the part of the needle thread loop leading to the material is at least as long as the part that extends to the thread supply. Since the end of the needle thread that remains with the thread supply must be of a length that insures the forming of the starting stitches of the next following sewing cycle, there results an undesired length for the needle thread end remaining on the sewing material due to the almost central separation of the needle thread loop which for certain sewing operations requires a shortening of the needle thread end that must be effected manually. Beyond that, the thread catcher that moves above the upper surface of the bobbin housing makes it necessary to place the looper lower which is not advantageous due to the displacement of the thrust of the needle movement for reasons of sewing technique.

SUMMARY OF THE INVENTION

It is therefore an object of the invention to provide a thread cutting means for double step stitch sewing machines having a looper that rotates in a horizontal plane which makes it possible to seize the part of the needle thread loop leading to the material and the looper thread by means of only one thread catcher that does not influence the level or height of the looper.

10 In order to accomplish this, the invention is based on the technical problem to so constitute the course of the looper thread from the bobbin housing to the stitch hole, while insuring flawless stitch formation, that the looper thread together with the part of the needle thread loop leading to the sewing material can be seized with a thread catcher that moves laterally of the bobbin housing.

This problem is solved in accordance with the invention in that the aperture for the looper thread is arranged below the plane of the surface of the bobbin housing at the part of its casing surface facing the needle, preferably in the area of the retaining finger, and the point of the thread catcher is movable below the plane of the surface of the bobbin housing between the path of movement of the needle and the retaining finger of the bobbin housing.

20 With double stitch loopers of the type referred to above, the looper thread is guided from the bobbin disposed in the bobbin housing through a slot that is usually directed obliquely upwardly in the housing surface of the upper part of the looper housing below its tensioning spring through to an outlet opening provided on the surface of the bobbin housing in the area of the abutment lug for the bobbin housing vent and from there extends obliquely upwardly to the stitch hole.

25 With the former looper construction, the looper thread extends from its outlet opening practically in the same plane as

30 the part of the needle thread loop that moves during guidance of the needle thread around the bobbin housing over its surface to the thread supply. With the arrangement of the aperture for the looper thread in accordance with the invention,

35 the looper thread leads from its aperture provided at its part of

40 its housing surface facing the needle below the plane of the bobbin housing surface between the housing surface of the bobbin housing and the inner wall of the looper body through

45 to the stitch hole, thus, it extends to the stitch hole below the plane of the bobbin housing surface and thus also below the

50 part of the needle thread loop that is to be moved by the looper below the plane of the bobbin housing surface to the thread supply. If in this connection the looper thread outlet opening is arranged in the region of the retaining finger of the

55 looper housing closely above its bearing rib, then the looper thread emerging from its opening extends during the period of

60 greatest loop expansion of the needle thread nearly parallel to its part leading to the sewing material and is seizable in its re-

65 gion disposed between the stitch hole and the retaining finger of the bobbin housing together with the part of the needle

70 thread loop that leads to the sewing material. If due to dis-

75 placement of the retaining finger toward the center of the bob-

80 bin housing between the path of movement of the needle and the

85 retaining finger of the bobbin housing a passage space is

90 provided for a thread catcher, the thread catcher which moves

95 below the plane of the bobbin housing extending along a path

100 of movement in a straight line or arcuately in a horizontal

105 plane between the retaining finger of the bobbin housing and

110 the path of movement of the needle may seize the looper

115 thread as well as the part of the needle thread loop going to

120 the material being sewn. In this manner assurance is given that

125 on the one hand the thread catcher does not seize the part of

130 the needle thread loop leading to the thread supply, and on the

135 other hand the looper thread thus formed can during the nor-

140 mal sewing operation neither be seized by the point of the

145 looper that seizes the needle thread, nor by the horn con-

150 trolling the loop dropping movement of the needle thread.

In order to make the thread ends remaining on the sewing

155 material short and the ends remaining on the thread supply

optimally long, it is necessary to displace the cutting location of both threads from their location of seizure at the thread catcher in the direction of the stitch hole. An advantageous solution of this problem is obtained in that the thread catcher has a recess, known per se, extending in the direction of its point with a terminal edge forming the counter cutter for the cutter and above the thread catcher a thread guide with a thread guiding surface is arranged which during the pull-out movement of the thread catcher moves above its recess along a path of movement parallel to its path of movement oppositely to the thread catcher. If already one thread catcher with a thread guide surface arranged in a fixed position would insure that the threads to be cut that extend from their point of seizure on the thread catcher obliquely upwardly come to rest in the recess, then the thread guide surface of the thread guide that moves opposite to the thread catcher affords in addition the security that the threads are not clamped between the thread catcher and the thread guide, and are not squeezed off at a location that is not predetermined.

In order to obtain extremely short thread ends, the cutter is arranged in accordance with a further development of the invention between thread guide and the thread catcher and movable during the withdrawing movement of the thread catcher upon a course of movement extending parallel thereto. In this manner it is possible to sever the threads closely below the stitch hole so that the thread ends remaining on the sewing material are only of a length that corresponds essentially to the thickness of the stitch plate and to the vertical difference between the bottom side and the top side of the thread catcher.

An arrangement of thread catcher, thread guide and cutter which is structurally simple and space saving, which simultaneously provides the opportunity of driving the parts moving oppositely to one another by means of a single rocking shaft, while interconnecting only two drawbars is obtained, in that thread catcher, thread guide and cutter are arranged coaxially to one another and movable along paths of movement that extend eccentrically to the looper.

In the arrangement in accordance with the invention of the aperture for the looper thread provided in the looper housing, care must be taken in addition besides the correct looper thread course that the bobbin with the looper thread supply can be readily inserted into the upper part of the looper housing and can be inserted in the looper housing bottom part in as completely threaded condition as possible. This requirement is met in accordance with a further feature of the invention that the bobbin housing bottom is provided laterally of the retaining finger with a recess that reaches up to its bearing rib and the looper housing top has a bridge that extends into this recess on whose lower end the aperture forming the looper thread guide for the looper thread is formed.

BRIEF DESCRIPTION OF THE DRAWINGS

The invention is described more in detail with reference to an embodiment illustrated in the drawings in which

FIG. 1 is a front view of a sewing machine,

FIG. 2 is a perspective illustration of the thread cutting arrangement and of its drive mechanism,

FIG. 3 is a perspective exploded view of the individual parts of the thread cutting device,

FIG. 4 is a perspective illustration of a first embodiment of a bobbin housing,

FIG. 5 is a perspective illustration of a second embodiment of a bobbin housing,

FIG. 6 is a plan view of a part of the bottom of the housing in accordance with FIG. 5,

FIG. 7 is a section through a looper with the bobbin housing in accordance with FIG. 4,

FIG. 8 is a perspective illustration of the thread cutting device shortly before the threads are seized,

FIG. 9 is a perspective illustration of the thread cutting device during the withdrawing movement, and

FIG. 10 is a side view of FIG. 4 with the thread cutter partly in section shortly before the cutting of the threads.

DESCRIPTION OF THE INVENTION

The standard 2 of the sewing machine is mounted on the base plate 1 (FIG. 1) on which the horizontal arm 3 is formed that has head 4 at its end. In the arm 3 the armshaft 5 is journaled which is in driving connection with the needle bar 7 that carries thread guiding needle 6 which moves up and down in the head 4. In the head of the sewing machine there is furthermore mounted the take-up lever 8 for the thread that cooperates with the needle in a known manner. Upon the armshaft 5 a belt wheel 9 is secured which transmits by way of a belt 10 and a wheel 11 the driving movements of the armshaft to the looper drive shaft 12 journaled in the base plate 1. The looper drive shaft 12 supports a pinion 13 which meshes with a cooperating pinion 15 disposed upon a vertical looper shaft 14 and thus drives the double stitch looper 16 which is mounted at the upper end of the looper shaft 14 and rotates in a horizontal plane.

The double stitch looper 16 (FIG. 7) has a looper body 17 on which a looper point 18 is formed. In the double stitch looper 16 a bobbin housing 21 is journaled which is defined by a bobbin housing bottom portion 19 and a bobbin housing upper portion 20, and which has a retaining finger 22 at its surface that faces the needle 6, which finger rests against an abutment 23 of the stitch plate 24 and secures the bobbin housing 21 against rotary movements. The lower part 19 of the bobbin housing has a bearing rib 25 which engages a guide groove 28 formed by the looper body 17 and the cover segment 27 that carries the looper horn 26. Furthermore, a side wall 29 is provided on the lower part 19 of the looper housing which supports at its upper end an abutment lug 30 for the housing member 31. The upper part 20 of the bobbin housing has a slot 33 along its side wall 32 (FIG. 4) that extends obliquely upwardly and which ends below a tensioning spring 34 for the looper thread in a bore 35 provided in the side wall 32. In the embodiment illustrated in FIG. 4 of the bobbin housing 21, the side wall 29 of the lower part 19 of the housing is provided with a recess 36 between the stop finger 22 and the abutment 30 for the housing member 31 into which projects a downwardly extending bridge 37 that extends closely above the bearing rib 25 that is provided on the upper part 20 of the bobbin housing. This bridge has an outlet opening 38 for the bobbin thread in the area of its lower end. The looper thread received by the bobbin 39 arranged in the bobbin housing 21 is guided from the bobbin through the obliquely upwardly extending slot 33, respectively the bore 35 of the upper part 20 of the bobbin housing, and from there below the tension spring 34 to a thread guide 40 provided on the upper part of the bobbin housing, and thence behind the side wall 29 of the lower part 19 of the bobbin housing to the looper thread outlet opening 38 formed on the bridge 37 of the upper part of the bobbin housing and from there extends in the manner reflected by FIGS. 4 and 7 between the inner wall of the looper body 17 and the bobbin housing 21 through to the stitch hole 41 in the stitch plate 24.

In the second embodiment of a looper housing illustrated in FIGS. 5 and 6, it is likewise formed by the lower part 119 of the bobbin housing and an upper part 120 of the bobbin housing and has a retaining finger 122 at its wall surface facing the needle 6 which rests against an abutment 23 of the stitch plate 24 and thus secures the bobbin housing 121 against rotating. The lower part 119 of the bobbin housing 129 is likewise provided with a bearing rib 125 that engages a guiding groove 28 formed by the looper body 17 and the cover segment 27 that supports the looper horn 26 which is fastened thereto. On the lower part 119 of the looper housing a side wall 129 is also provided which at its upper end supports an abutment lug 130 for the housing member 31. The upper part 120 of the bobbin housing has a slot 133 along its side wall 132 that extends obliquely upwardly, which terminates below a tension spring

134 for the looper thread in a bore 135 provided in the side wall 132. Laterally of this bore 135, a further bore 136 is provided in the side wall 132 of the upper part 120 of the bobbin housing which serves for receiving the offset end of the tension spring 134 which has a recess in the area of this end that forms a thread guide 140. At the side wall 129 of the lower part 119 of the bobbin housing, a rib 137 is provided that extends essentially parallel to the bearing rib 125 below the abutment lug 130, which terminates in the area of the side wall 129 of the bobbin housing between the retaining finger 122 and the lug 130, and has at its end an aperture 138 forming a guide for the looper thread formed in a manner reflected by FIG. 6. The looper thread in this embodiment of the bobbin housing extends from the bobbin 139 disposed therein through the slot 133, respectively the bore 135, below the tension spring 134 to the thread guide 140 arranged at its end, and thence along the lower side of the rib 137 to the aperture 138 defined at the end thereof and leading from there between the inner wall of the looper body 17 and the bobbin housing 121 in a manner illustrated by FIG. 5, obliquely upwardly to the stitch hole 41 of the stitch plate 24.

At the bottom side of the base plate 1, a supporting plate 45 (FIG. 2) is secured which has two grooves 46, 47 that extend arcuately and concentric relative to each other which are eccentric with respect to the double stitch looper 16. The lower groove 46 that is disposed in a horizontal plane serves as a guide path for a thread catcher 48 that is provided therein, whose point 49 swings below the plane of the surface of the bobbin housing 21, 121 in a path of movement which extends between the retaining finger 22, 122 and the stitch hole 41 of the stitch plate 24. The thread catcher 48 (FIG. 3) has a recess forming a counter hook 50 at its lateral surface that faces the needle 6 which connects with a groove 51 extending in the direction of the point 49 and which in turn ends in a bore 52. The terminal edge of the recess 51 or the bore 52 defines a counter edge 53 for a cutter 54 that cooperates with the thread catcher 48. At the end remote from its point a receiving bore 55 for a stud 56 is provided on the thread catcher 48 which projects through an arcuately extending slot 57 of the support plate 45 arranged in the groove 46 and is received by a drawbar 58.

The cutter 54 (FIG. 3) arranged above the thread catcher 48 is likewise of arcuate shape and is received in the upper groove 47 of the support plate 45 which is wider with respect to the lower groove 46. For driving the cutter 54 which has an edge 59, it is provided with a bore 60 which is engaged by a stud 61 that projects through a slot 62 which is likewise arcuately shaped and is arranged laterally of the groove 46 in the groove 47 and is in its turn mounted on a drawbar 63.

Above the cutter 54 a thread guide 64 with a point 65 and a thread guide surface 66 adjacent thereto is arranged in the groove 47 which receives the same. The arrangement of the thread guiding surface 66 is of such nature that it moves during the relative opposite movements of thread catcher 48 and thread guide 64 directly above the recess 51 in the thread catcher along a path that is parallel to their path of movement. The thread guide 64 has a bore 67 for its operation which is engaged by the stud 61 that projects into the bore 60 of the cutter 54.

As shown particularly in FIG. 2, a leaf spring 68 is provided upon the upper surface of the supporting plate 45 which rests upon the thread guide 64 and thereby holds the thread catcher 48, the cutter 54 and the thread guide 64 in the grooves 46, 47 coordinated therewith. At the lower side of the support plate 45 a further leaf spring 69 is secured which serves to clamp the looper thread at the end of the withdrawing movement of the thread catcher 48 at the lower side of the support plate 45.

For driving the thread catcher 48, respectively the cutter 54 and the thread guide 64, the two drawbars 58, respectively 63, which are engaged by the studs 56, 61 are linked to a crank 72 in a manner shown in FIGS. 2 and 3 which is carried on a rocking shaft 74 engaging a support member 73 secured to the

base plate 1. At its lower end the rocking shaft is provided with a crank arm 75 which is engaged by a drawbar 76. The free end of the drawbar 76 is connected with a bifurcated member 77, which is linked to the drawbar of an electromagnet 78, which in turn is secured to the lower side of the base plate 1 by means of a support member 79. Between the support member 79 and a setting ring 80 provided on the bifurcated member 77, a spring 81 is arranged which is tensioned during the thread seizing movement of the thread catcher 48, and then controls the thread withdrawing and cutting movement of the thread catcher. It is, of course, also possible to carry out the movements of the thread catcher 48, respectively the cutter 54 and the thread guide 64 with a four-joint transmission that is in releasable connection with the main shaft of the sewing machine and which engages the crank arm 75 or the drawbar 76.

The manner of operation of the thread cutting device is as follows:

At the end of the seam the sewing machine is briefly stopped with the needle in a predetermined position, for example with the needle in lowermost position by means of a stopmatik-motor; in this connection the circuit of the electromagnet 78 is closed simultaneously. The magnet pulls up and locks the crank arm 75 in clockwise direction as seen in FIG. 2. As a result, the crank 72 is thereupon likewise swung in clockwise direction about the crankshaft 74 and transfers the rocking movement by way of the drawbar 58 to the stud 56, to the thread catcher 48. The thread catcher effects a counter-clockwise movement as viewed in FIG. 8 and moves in this connection as seen in the direction of sewing from its starting position behind the stitch-forming location in the direction of the stitch hole 41. During this movement of the thread catcher 48, the needle 6 stitches again and the looper point 18 seizes the loop of the needle thread. During the guiding of the needle thread loop around the bobbin housing, the looper point 18 guides the part of the needle thread loop that leads to the needle thread supply over the top of the bobbin housing 21, 121. Shortly before the greatest expansion of the needle thread loop, the point 49 of the thread catcher 48 has reached the retaining finger 22, 122 of the bobbin housing 21, 121 and moves below the plane of the top surface of the bobbin housing between its retaining finger 22, 122 and the path of movement of the needle 6 through into the needle thread loop. The part of the needle thread loop leading to the thread supply extends in this connection from stitch hole 41 (FIG. 8) above the top side of the thread catcher 48 over the top side of the bobbin housing 21, 121 and thence to looper point 18. The part of the needle thread loop that leads to the sewing material extends from the looper point 18 at the bottom of the bobbin housing 21, 121 i.e. between the bobbin housing and the bottom of the looper body 17 through to the surface of the bobbin housing 21, 121 facing the needle 6, and from there between the bobbin housing and the inner wall of the looper body 17 through along the lower side of the thread catcher 48 to the stitch hole 41. The looper thread extends from its aperture 38, 138 provided on its bobbin housing 21, 121 likewise between the bobbin housing 21, 121 and the inner wall of the looper body 17 obliquely upwardly along the lower side of the thread catcher 48 to the stitch hole 41. The part of the needle thread loop and the looper thread leading to the material being sewn thus extend from the inner edge of the covering segment 27 below the point of the thread catcher 48 nearly parallel to one another (FIGS. 7 and 8) to the stitch hole and during the further course of the movement of the thread catcher 48 rest against the side surface that faces the needle, while they are simultaneously pushed by this lateral surface toward the stitch hole 41 and are thus tensioned. During the further course of the movement of the catcher, it pushes itself so far into the needle thread loop which drops due to the further turning of the looper 16 from the bobbin housing 21, 121 until that part that leads to the sewing material comes to rest together with the looper thread in the recess of the thread catcher 48 which forms a counter hook 50. The thread feeder 8 during this

movement of the thread catcher 48, with the needle thread tension open, pulls up the needle thread loop which is dropping down from the bobbin housing 21, 121 respectively from the looper. The cutter, as well as also the thread guide 64, execute a rocking movement due to their connection with the drawbar 63, respectively crank 72, which however is without influence on the seizing of the thread as also on the course of the threads to be seized and cut.

In the returning position of the thread catcher movement, the electromagnet 78 is devoid of potential as a result of which the spring 81 which is now released takes over the drive of the thread catcher 48, cutter 54 and thread guide 64. The thread catcher 48 moves back in the direction of its initial position against its first direction of movement, and this connection as the needle thread tension is open pulls up needle thread, as well as looper thread with its counter hook 50. The parts of needle and looper thread which extend from the counter hook 50 to the material being sewn now come into engagement with the thread guide surface 66 of the thread guide 64 that moves oppositely to the thread catcher 48 and during the withdrawing movement of the thread catcher 48 are pressed from the recess 51 provided above the thread catcher along a thread guide surface 66 which is parallel to its path of movement into the recess and thus is held away from the edge 59 of the cutter 54 which moves in opposite direction to the thread catcher 48, i.e. in the direction to the stitch hole 41. Thus, during the withdrawing movement of the thread catcher 48, the parts of needle and looper thread leading to the material being sewn are pressed by the thread guide surface 66 of the thread guide 64 into the recess 51 of the thread catcher, while the parts of the needle and looper thread which lead from the counter hook 50 of the thread catcher 48 to the thread supply extend along the lower side of the thread, while the part of the needle thread loop leading to the needle thread supply passes along the lower side of the thread catcher 48, and from there to the stitch hole 41, while the part of the looper thread leading from the counter hook 50 to the looper thread supply is clamped in between the leaf spring and the support plate 45 provided between the lower side and the support plate and leads from its clamping position below the plane of the surface of the bobbin housing 21, 121 between its housing surface and the inner wall of the looper body 17 through to the aperture 38, 138 provided on the bobbin housing 21, 121.

As soon as the thread take-up lever 8 has reached the upper region of its dead point, the edge 53 provided on the thread catcher 48, as well as also the cutter 54 which moves opposite to the thread catcher has reached with its edge 59 the region of the stitch hole 41 and severs in cooperation with the edge 53 of the thread catcher 48 the needle, as well as the looper thread. Since the ends of needle and looper thread remaining on the material being sewn lead from the cutting location of both threads directly to the stitch hole 41 and from there to the material, they become optimally short, while the ends of needle and looper thread remaining with the thread supply will be of a length insuring safe formation of the initial stitches of the next sewing cycle, due to the fact that they lead from the cutting location first within the recess 51 provided at the

top of the thread catcher 48 to the counter hook 50 and from there along the lower side of the thread catcher to the stitch hole 41, or by way of the thread clamp 69 to the looper exit opening 38, 138.

- 5 Upon cutting of both threads, the thread catcher 48 moves on in the direction of its thread withdrawing movement and returns to its starting position, while the thread guide 64, as well as also the cutter 54 reverse their direction of movement due to their linkage with the stud 61 of the drawbar 63, and 10 now moving in the same direction as the thread catcher 48 return likewise to their starting position.

Having now described our invention, what we desire to protect by letters patent is set forth in the appended claims.

We claim:

- 15 1. Thread cutting arrangement for double stitch sewing machines having a looper turning in a horizontal plane, a needle movable relative to said looper, a bobbin housing journaled in the looper, a stitch plate disposed above said looper having an abutment, said housing having a retaining finger for 20 engaging said abutment to secure the same against rotary movements and having an outlet opening for the looper thread determining the course of the looper thread between said stitch plate and said bobbin housing, a cutter below said stitch plate, a thread catcher having a catcher point movable in a 25 horizontal plane and cooperating with said cutter and having a recess for accommodating the needle and looper threads adjacent said point, where the opening for the looper thread is disposed below the plane of the surface of the bobbin housing on the housing surface facing said needle, and adjacent the 30 retaining finger, said point of said thread catcher being movable below the plane of the surface of the bobbin housing between the path of movement of the needle and of the retaining finger of the bobbin housing.

2. Thread cutting device in accordance with claim 1, where 35 said thread catcher has a groove on its upper surface extending in the direction of said point, said groove terminating in an edge defining a counter cutter for said cutter, a thread guide having a thread guiding surface disposed above said thread catcher movable above said groove along a path of movement 40 parallel to the path of movement thereof opposite to the path of movement of said thread catcher.

3. Thread cutting device in accordance with claim 2 where 45 said cutter is disposed between said thread guide and said thread catcher and movable in opposite direction during the pull-out movement of said thread catcher along a path of movement extending parallel to the path of movement of said thread catcher.

4. Thread cutting device in accordance with claim 3, where 50 said thread catcher, said thread guide and said cutter are arranged coaxially relative to one another and along paths of movement extending eccentrically to said looper.

5. Thread cutting device in accordance with claim 1, where 55 the lower part of said bobbin housing is provided with a bearing rib laterally of said retaining finger, a recess to which said finger extends, and the upper part of said bobbin housing has a bridge extending into said recess at the lower end of which said opening for the looper thread is provided.

UNITED STATES PATENT OFFICE
CERTIFICATE OF CORRECTION

Patent No. 3,658,021 Dated April 25, 1972

Inventor(s) Kristen Hedegaard, Anton Lessmeister

It is certified that error appears in the above-identified patent and that said Letters Patent are hereby corrected as shown below:

Amend the title of the application as follows:
—ARRANGEMENT FOR CUTTING THREADS ON LOCK STITCH SEWING MACHINES

Abstract, line 1: page 2, line 4; page 4, lines 6 and 27; and
Page 9, lines 14 and 15 change "double" to --lock--;

Page 2, line 5 delete "or catcher";

Page 3, line 15 change "stop" to --retaining--;

Page 5, line 3 delete "housing vent" and insert instead
--member finger--;

Page 9, line 26, and Page 10, line 2 and lines 30/31, change
"housing member" to --bobbin member finger--;

Page 10, line 2 change "stop" to --retaining--;

Page 15, line 19 delete "thread feeder" and insert instead
--take-up lever--;

Claim 1, line 1 change "double" to --lock--;

Claim 2, line 7 change "path" to --direction--.

Signed and sealed this 15th day of August 1972.
